UNITED STATES PATENT OFFICE.

JOHN B. MCFERRAN, JR., OF LOUISVILLE, KENTUCKY.

POWER-DRIVEN AGITATING MECHANISM.

1,420,270.

Specification of Letters Patent. Patented June 20, 1922.

Application filed June 23, 1921. Serial No. 479,772.

To all whom it may concern:

Be it known that I, JOHN B. MCFERRAN, Jr., a citizen of the United States, residing at Louisville, in the county of Jefferson and 5 State of Kentucky, have invented certain new and useful Improvements in Power-Driven Agitating Mechanism, of which the following is a specification.

The present invention relates more particularly to power-driven agitating mechanism such as ice cream freezers, and other analogous apparatus, and the object is to provide mechanism that is simple in construction and adaptable for use with the 10 ordinary freezer or other structures, thus making it peculiarly applicable to domestic purposes.

In the accompanying drawings, two embodiments of the invention are shown, 20 wherein:—

Figure 1 is a plan view of an ice cream freezer complete,

Figure 2 is a side elevation of the same,

Figure 3 is a plan view on an enlarged 25 scale with parts removed, illustrating one form of the gear mechanism,

Figure 4 is a sectional view through the structure illustrated in Figure 3,

Figure 5 is a plan view with parts re- 30 moved and with parts broken away of a different form of construction,

Figure 6 is a vertical sectional view through the mechanism illustrated in Figure 5.

35 In the drawings, an ordinary ice cream freezer tub 7 is illustrated, which in Figures 2, 3 and 4 contains a rotatable can 8, in which is placed a fixed agitator 9. The tub is provided on one side with a pair of 40 fixed hooks 10, and on the other side with a swinging latch 11.

A support in the form of a bridge piece 13 is adapted to be placed on the tub and has at one end a head 14 provided with 45 sockets 15 to receive the hooks 10. Its other end is provided with an opening 16 to receive the latch 11, whereby the bridge piece is effectively mounted on the tub.

This bridge piece has an integral upstand- 50 ing casing 17 and a depending boss 18. In the latter is journaled a tubular shaft 19 having at its upper end a gear 20 that is located in the casing 17, its lower end terminating in clutch teeth 21 adapted to interlock with corresponding teeth 22 formed on the cover 23 of the can. A cover 24,

located on the casing 17, constitutes a support for an electric motor, the housing of which is designated 25, and which motor may be of any desired character. This 60 motor has attached thereto a cord 26 provided with a suitable plug 27 which can be inserted in any well known electrical socket. A controlling switch of any desired character is shown at 28. The top of the motor 65 casing 25 is in the form of a handle 29.

The shaft of the motor is shown at 30, and is journaled in the top 31 as shown at 32. The lower end of this shaft is provided with a pinion 33 that meshes with a gear 70 wheel 34. This gear wheel carries a pinion 35 in mesh with another gear 36. The gear 36 has fixed thereto a pinion 37 in mesh with the gear wheel 20. It will thus be seen that the motor will effect the rotation of the can 75 8 through the train of gearing housed within the casing 17.

The agitator 9 has a shaft 38 that extends into the hollow shaft 19 and terminates in an angular portion 39 detachably received 80 in the socket 40 of a bracket 41 fixed within the casing 17. The agitator is thus held against rotation.

In the embodiment illustrated in Figures 5 and 6 the can and agitator are rotated in 85 opposite directions. In this embodiment of the invention the tub is designated 42 and has detachably mounted thereon the bridge piece 43 carrying the housing 44, said housing having a top 45 supporting the motor, 90 the casing of which is designated at 46. The motor shaft is designated 47 and terminates in a pinion 48 that is in mesh with a gear wheel 49. This gear wheel has a pinion 50 meshing with a gear wheel 51 that carries 95 a long pinion 52. The pinion 52 is in mesh with an idler 53 that operates a gear 54 on the upper end of a shaft 55 that detachably interlocks with the agitator 56. The pinion 52 is also in direct mesh with a gear 57 carried by the upper end of a tubular shaft 58, clutched, as shown at 59, to the top 60 of the can 61. With this construction, it will be evident that the can will be rotated in one direction and the agitator in an opposite direction.

From the foregoing, it is thought that the construction, operation and many advantages of the herein described invention will be apparent to those skilled in the art, without further description, and it will be understood that various changes in the size,

shape, proportion and minor details of construction, may be resorted to without departing from the spirit or sacrificing any of the advantages of the herein described invention.

Having thus fully described my invention, what I claim as new, and desire to secure by Letters Patent, is:

1. In apparatus of the character described, 10 the combination with a supporting bridge having means at its ends for engagement with a container, of a gear casing on said bridge, a motor mounted on the gear casing and including a housing terminating at its 15 top in a handle, gearing within said casing driven by the motor, and means operated by the gearing for engagement with a movable member of the device to which it is applied.
- 20 2. In apparatus of the character described, the combination with a supporting bridge having means at its ends for engagement with a container and a central depending boss, a gear casing mounted on said bridge, 25 a tubular shaft element journaled in said boss and having a terminal clutch for engagement with the movable member of the device to which it is applied, an agitator engaging member within the shaft element, 30 a train of gearing in the gear casing engaged with the shaft element, a cover for the gear casing, and a motor on the cover having a housing and also a shaft geared to the train of gearing.

3. In apparatus of the character described, 35 the combination with a supporting bridge having means at its ends for engagement with a container, a central depending boss and upstanding walls forming a chamber, 40 of a gear casing supporting a train of gearing within the chamber and forming a cover for the same, a motor mounted on said cover, and means for gearing the motor to the train of gearing and the latter to the movable member of the device within the container. 45

4. In apparatus of the character described, 50 the combination with a supporting bridge having means at its ends for engagement with a container and a central depending boss, a gear casing mounted on said bridge, 55 a tubular shaft element journaled in said boss and having a terminal clutch for engagement with a movable member of the device to which it is applied, an agitator engaging member within the shaft element, a train of gearing within the casing engaged with the shaft element and also with the agitator engaging member to rotate them in opposite directions, a cover for the gear casing, a motor on the cover having a shaft 60 geared to the train of gearing.

In testimony whereof, I affix my signature in the presence of two witnesses.

JOHN B. McFERRAN, JR.

Witnesses:

C. HELENE STRATER,
MARY F. HARRINGTON.
